(57) **CLAIM**

I claim the ornamental design for a keder, as shown and described.

DESCRIPTION

FIG. 1 is a side perspective view of a keder of our new design;

FIG. 2 is a side elevation view of the keder of FIG. 1;

FIG. 3 is a side elevation view of the keder of FIG. 1;

FIG. 4 is a rear elevation view of the keder of FIG. 1;

FIG. 5 is a front elevation view of the keder of FIG. 1;

FIG. 6 is a top plan view of the keder of FIG. 1;

FIG. 7 is a bottom plan view of the keder of FIG. 1;

FIG. 8 is a perspective view of the keder of FIG. 1 without the outer wrap;

FIG. 9 is a rear elevation view of the keder of FIG. 8;

FIG. 10 is a front elevation view of the keder of FIG. 8;

FIG. 11 is a top plan view of the keder of FIG. 8;

FIG. 12 is a bottom plan view of the keder of FIG. 8;

FIG. 13 is a front elevation view of the keder of FIG. 1 attached to a material with additional kders; and,

FIG. 14 is a side perspective view of the kders and material of FIG. 13.

The dashed lines in FIGS. 1-7 and 13-14 depict environment to show the placement of the claimed design.

The dot-dash-dot lines in FIGS. 1 and 4-12 depict portions of the keder that form no part of the claimed design. The keder is shown with a symbolic break in its length. The appearance of any portion of the keder between the break lines forms no part of the claimed design.

1 Claim, 13 Drawing Sheets
